UNITED STATES PATENT OFFICE.

JAMES D. McFARLAND, JR., OF FRUITVALE, CALIFORNIA, ASSIGNOR TO AFLOAT MOTOR CO., OF OAKLAND, CALIFORNIA, A CORPORATION OF CALIFORNIA.

WAVE-MOTOR.

937,712.

Specification of Letters Patent. Patented Oct. 19, 1909.

Application filed March 4, 1908. Serial No. 419,194.

To all whom it may concern:

Be it known that I, JAMES D. McFARLAND, Jr., a citizen of the United States, residing at Fruitvale, county of Alameda, State of California, have invented certain new and useful Improvements in Wave-Motors, of which the following is a specification.

My invention relates to means by which the tipping or rocking motion produced on a float, boat, or ship, by the action of the waves, is converted into rotary motion; it will be more exactly understood by reference to the accompanying drawings, in which—

15 Figure 1 is a vertical section of my machine on line $x-x$ of Fig. 2. Fig. 2 is a plan view of the mechanism, the deck of the float being broken away. Fig. 3 is a detail view of knuckle-joint. Fig. 4 is a section of 20 knuckle-joint on line $z-z$ of Fig. 3. Fig. 5 is a section and plan on line $x-x$ of Fig. 4. Fig. 6 is a detail of the governor and by-pass valve connections.

25 My invention consists of a float, or boat, as 1, on which is universally pivoted, at 8, the hanging lever or pendulum 2 which hangs through an opening in the bottom of the float to any desired depth, and carries on its lower end the cross-arms or blades 3, 30 the function of which is to hold the pendulum still, or approximately so, as the float is rocked by the waves. This is done by reason of the large vertical surfaces presented to the water in all horizontal directions by the 35 blades 3. The upper and lower edges of the cross are sharp or knife-like, and offer very little resistance to the rising and falling of the float.

40 The upper end of the pendulum above the fulcrum 8 is slidable loose in a sleeve 4 which forms part of a universal knuckle-joint. The sleeve is pivoted in a ring 5 which in turn is pivoted at right angles to the sleeve pivots to the outside ring 6, 45 through which are a series of holes 7 (Fig. 3) for the reception of the pins by which the pump pitmen 9 are connected up to the pendulum. There are four of these holes 7 in the present instance, but their number 50 will vary with the number of pumps used in the motor. The parts 4—5—6 constitute my universal knuckle-joint or connections between the pendulum and the pump pitmen.

55 The universal fulcrum 8 for the pendulum

or lever comprises a sleeve immovably keyed or bolted to the pendulum, and which sleeve is pivoted in a ring 8' similar to ring 5, and ring 5 being pivoted at right angles to the sleeve pivots in the frame of the float. Thus 6x it is seen that the pendulum has a universal fulcrum accommodating the pendulum to the tossing and tipping of the float in any and all directions.

65 The pitmen 9 are connected to pistons or plungers within the respective pump cylinders 13 radially disposed around the upper end of the pendulum. The chambers of the cylinders behind the pistons are connected to a common source of fluid supply contained 70 in a conduit 17, and they each discharge into a common outlet or exhaust pipe 18, leading to a three-cylinder engine 19, from whose exhaust the fluid is again led back through pipes 20—20^a to reservoir 17; the top cylinder 75 of the engine exhausting through pipe 20^a to 17. The intake and outlet of the engine are through valves 22 and 23 opened at the proper intervals by connecting rods to an eccentric on the engine shaft, in a manner 80 well known in the art. The intake of each pump is through a respective valve 24, and outlet through 25; these valves are automatic in action.

85 I have shown the motor in this instance as used in driving a multipolar dynamo 26, from which the electric current generated may be taken ashore through a cable and used as desired. The speed of such a dynamo should 90 be high, and as nearly constant as possible, for the reason that the engine cylinders and the inlet and exhaust pipes and ports are all of about the same diameter, and as the waves are slow in movement, the volume of the engine cylinders is very much less than that of 95 the pumps, which will have the effect of causing many turns of the engine at each slight movement of the pump plungers. A by-pass or shunt is provided at 27, closed by stop-cock 28, acted on by the ball governor 29, which receives its motion through 100 any suitable connections, as 29', from the engine shaft. The governor is set so that the slowest, or least practical movement of 105 the plungers will run the dynamo at its normal speed. As the action is increased, the governor acts on the stop-cock through suitable connections, represented at 30, opening said stop-cock and shunting a portion of the fluid through pipe 27 to reservoir 17, thus 110

keeping the speed of the dynamo constant. As shown in Fig. 6, the connections 30 comprise a slotted arm rigid with the governor sleeve and pivotally connected with the stem 5 of valve 28.

In using my device as thus constructed, I prefer to fill reservoir 17 with oil, which may be done through an opening which is then closed by a plug, as shown at 21. The oil 10 acts as a good lubricant, and will prevent rusting, giving the machine a much longer life than if water were used; but a pipe may be connected to 17, thence out of the float to the water, and the engine could be caused to 15 exhaust to the outside of the float.

From the foregoing it will be manifest that no matter in which direction the float rocks or tips under the constant motion of the waves, the cross-arms will operate to 20 maintain the pendulum approximately perpendicular, and to anchor it against the relative motion of the float, so that the float is in the nature of a universally fulcrumed lever and acting through the universal joint 25 connection with the pumps to keep one or more of the pumps continuously in operation to supply fluid pressure to the engine.

Having thus described my invention, what I claim and desire to secure by Letters Patent 30 is—

1. In a wave motor, the combination of a float or buoyant body, a pendulum fulcrumed thereon to swing in all directions, and mechanism on the float connected to the 35 pendulum by which the relative movements of the float and pendulum with respect to one another are translated into rotary motion, said mechanism comprising an engine and a part operated thereby.

40 2. In a wave motor, a float or buoyant body, a pendulum fulcrumed thereon to swing in all directions, and mechanism on the float and connected to the pendulum by which the relative movements of the float 45 and pendulum with respect to one another are translated into rotary motion, said mechanism comprising an engine, and a pump connected with the pendulum, said pump having valve connections with a source of 50 fluid supply, and the pump having fluid connections with the engine.

55 3. The combination of two connected members, said members comprising a universal joint and said members having a universal 60 fulcruming action in said joint with respect to one another, and means by which the oscillating motions of either member with respect to the other are translated into rotary motion.

65 4. The combination of a part to be rotated, a support for said part, a member mounted for universal oscillation upon said support, and mediate mechanism between the oscillating member and said part to be rotated for

rotating the latter on the movement of the oscillating part.

5. In a wave motor, the combination of a float or buoyant body, a pendulum, means for suspending the pendulum on the body by which the pendulum may oscillate to all 70 points of the compass, means for maintaining the pendulum approximately normal and yet allow the float to rock in any direction around the pendulum, and means connected with the pendulum for translating 75 the oscillations of the float into rotary motion.

6. In a wave motor, the combination of a float or buoyant body, a pendulum, means for suspending the pendulum on the body 80 by which the pendulum may oscillate to all points of the compass, means for maintaining the pendulum approximately normal and yet allow the float to rock in any direction around the pendulum, and means connected with the pendulum for translating 85 the oscillations of the float into rotary motion, said last-named means including a series of pumps connected by a universal joint to the pendulum, an engine having fluid 90 connections with the pumps and operated by fluid pressure from the pumps, and a shaft driven by the engine.

7. The combination of a suitable support, a series of radially arranged pumps, the 95 pumps connected with a universal joint, an actuator connected with said universal joint, said actuator having a universal fulcrum by which the pumps are operated on the operation of the actuator about its fulcrum in any 100 direction, and an engine having fluid connections with the pumps.

8. The combination of a series of radially arranged pumps, a centrally arranged connector for the pump pitmen, an actuator 105 connected with said central connection, the pumps having inlets connecting with the source of fluid supply, an engine, connections between the pumps and the engine for operating the engine by the fluid discharged 110 by the pumps, and the engine having an exhaust back into said source of fluid supply.

9. The combination of a series of radially arranged pumps, a centrally arranged connector for the pump pitmen, an actuator 115 connected with said central connection, the pumps having inlets connecting with the source of fluid supply, an engine, connections between the pumps and the engine for operating the engine by the fluid discharged 120 by the pumps, the engine having an exhaust back into said source of fluid supply, and means controlled by the engine for limiting the supply of fluid from the pumps to the engine.

10. In a wave motor, the combination of a float, a pendulum universally fulcrumed thereon, a series of pumps arranged radially

with respect to the pendulum, the pumps having pitmen universally connected with the pendulum; an engine, and fluid connections between the engine and pump cylinders, said cylinders having inlet connections with the source of fluid supply.

11. In a wave motor, the combination of a float, a pendulum universally fulcrumed thereon, a series of pumps arranged radially 10 with respect to the pendulum, the pumps having pitmen universally connected with the pendulum, an engine, fluid connections between the engine and pump cylinders, said cylinders having inlet connections with the 15 source of fluid supply, and a relief valve by which the excess fluid pumped by the pumps is diverted from the engine.

12. In a wave motor, the combination of a float, a pendulum universally fulcrumed thereon, a series of pumps arranged radially 20 with respect to the pendulum, the pumps having pitmen universally connected with the pendulum, an engine, fluid connections between the engine and pump cylinders, said cylinders having inlet connections with the 25 source of fluid supply, a relief valve by which the excess fluid pumped by the pumps is diverted from the engine, and connections with the engine for operating the relief valve.
